CLAIM

The ornamental design for an octagonal beam wheel assembly for a shower door, as shown and described.

DESCRIPTION

FIG. 1 is a front elevation view of an octagonal beam wheel assembly embodying my new design;

FIG. 2 is a side elevation view of the octagonal beam wheel assembly disclosed in FIG. 1;

FIG. 3 is front perspective view of the octagonal beam wheel assembly of FIG. 1.

FIG. 4 is a rear perspective view thereof showing a cylindrical central channel; and,

FIG. 5 is a perspective view of the octagonal beam wheel assembly of FIG. 1.
